UNITED STATES PATENT OFFICE.

GEORGE ADISON DONALDSON, OF GIRARD, ILLINOIS.

SHUTTLE.

1,144,178.

Specification of Letters Patent. Patented June 22, 1915.

Application filed August 12, 1914. Serial No. 856,360.

To all whom it may concern:

Be it known that I, GEORGE A. DONALDSON, a citizen of the United States, and a resident of Girard, in the county Macoupin 5 and State of Illinois, have invented a new and Improved Shuttle, of which the following is a full, clear, and exact description.

This invention relates to improved shuttles or bobbins and more particularly to 10 tatting shuttles.

The object of the invention is to improve, 15 simplify and cheapen shuttles of this character, as well as to provide a novel connection between portions thereof whereby they may be conveniently separated but held sufficiently tight to prevent accidental separation or displacement thereof.

With the above and other objects in view, 20 the invention resides in the peculiar combination and arrangement of parts to be hereinafter more fully described, illustrated and claimed, it being also an object to provide a device which is simple in construction, durable and efficient.

25 Reference is to be had to the accompanying drawings forming a part of this specification, in which similar characters of reference indicate corresponding parts in all the views, and in which—

30 Figure 1 is a side elevation of a shuttle or bobbin constructed in accordance with my invention; Fig. 2 is a sectional view on the line 2—2 of Fig. 1; Fig. 3 is a sectional view on the line 3—3 of Fig. 1.

35 As illustrated, the improved tatting shuttle or bobbin consists of two opposed shells or elongated and oppositely tapered plates 5 and 6, said shells or plates being provided with means to detachably connect them so as 40 to permit them to be separated for conveniently winding the thread or cord thereon but to prevent accidental separation or displacement of the shells or plates with respect to each other.

45 For the above purpose, the shell or plate 5 is provided with an elongated sleeve extension 7 projecting laterally from the central portion thereof and shaped similarly in cross section to the shape of the plate in plan. 50 This sleeve is provided with a slot 8 adjacent to one of its tapered ends, said slot extending partly into the sleeve as shown in Fig. 3 of the drawings. The other shell or plate is provided with a laterally extended 55 elongated sleeve 9 which is of larger cir-

cumference or size than the sleeve 7 so as to snugly receive the latter therein in telescopic relation and frictionally hold the parts together, while the slot 8 permits the sleeve 7 to be expanded so as to vary its size 60 to insure the proper friction to hold the parts together and prevent accidental separation or displacement thereof. The sleeves together produce an intermediate reduced portion or spool between the shells or plates 65 but this is further provided for by the provision of a flange 10 at the free end of the sleeve 9 which is substantially diamond-shaped in plan and which is also provided with an opening or aperture 11 for the purpose of inserting the thread and anchoring the end thereof between the flange and the shell or plate 5 when starting or winding the thread or material on the shuttle or bobbin.

70 From the foregoing it will be seen that each shell or plate is thus provided with a hollow tube, the two projecting in opposite directions to be telescoped together so that by removing one side, that is, the plate or shell 5 and its tube, the shuttle can be filled or wound with the thread or material much faster and easier than ordinary shuttles, by holding the shell or plate 6 in one hand and winding the thread or material with 75 the other, while the flange 10 prevents displacement thereof from the tube 9. The slot permits expansion or contraction of the tubular extension 7 whereby it will be caused to properly engage the interior wall 80 of the tube or tubular extension 9 to positively hold the parts together when engaged with one another to cause the plates or shells to meet at their ends as is more particularly 85 shown in Fig. 1.

90 Having thus described my invention, what I claim as new and desire to secure by Letters Patent is:—

1. A tatting shuttle or bobbin, comprising 95 two elongated plates having tapering ends, each plate having a tubular extension adapted to telescope, the tubular extensions being of a shape in cross section similar to the shape of the plates and one of the said extensions being slotted.

100 2. A tatting shuttle, comprising elongated tapered plates each provided with an elongated lateral tubular extension having tapering ends and adapted to telescope one 105 within the other, one of the extensions hav-

ing a slot adjacent one tapered end, and a flange at the free end of one extension to contact with the plate of the other extension and provide for the retention of the thread 5 or material wound thereon.

In testimony whereof I have signed my

name to this specification in the presence of two subscribing witnesses.

GEORGE ADISON DONALDSON.
